UNITED STATES PATENT OFFICE.

CHARLES J. RICHMAN, OF OAK PARK, ILLINOIS.

DESIGN FOR A CAP.

49,674.

Specification for Design. Patented Sept. 19, 1916.

Application filed May 20, 1916. Serial No. 98,962. Term of patent 3½ years.

To all whom it may concern:

Be it known that I, CHARLES J. RICHMAN, a citizen of the United States, and a resident of Oak Park, Cook county, State of Illinois, have invented a new, original, and ornamental Design for Caps, of which the following is a specification, reference being had to the accompanying drawing, forming a part thereof.

I claim:

The ornamental design for a cap, as shown.

In testimony whereof I have signed this specification.

CHARLES J. RICHMAN.
